UNITED STATES PATENT OFFICE

1,936,434

METHOD OF FORMING TEXTILE NETWORK

Edward Jumonville, New Orleans, La.

Application December 9, 1932. Serial No. 646,427

2 Claims. (Cl. 112—262)

This invention relates to methods of forming network, particularly to that used in the manufacture of mops.

The object of the invention is, however, to provide a practical method for economically producing large quantities of network adapted to various uses.

The invention consists, broadly speaking, in laying a plurality of substantially parallel lengths or stretches of yarn strand, sewing the same transversely with a plurality of substantially parallel rows of stitching; severing, in one set of alternate rows, stitches between alternate strands and, in the other set of alternate rows, severing stitches oppositely to the unsevered stitches in the first said set.

This will convert the fabric into network.

Many different forms of apparatus may be used to perform the improved method. These may vary with the size of the yarn strands and meshes, the purpose of the network and whether the network is formed continuously, intermittently or in units.

A simple embodiment of the invention and some apparatus useful in its operation are hereinafter described and illustrated for the purpose of disclosure.

In the drawing:

Fig. 1 shows a plurality of yarn strands laid in substantially parallel rows and cross stitched.

Fig. 2 shows the cross stitching re-inforced with tape.

Fig. 3 is a diagram indicating severance of the cross stitching to convert the fabric into network.

Fig. 4 shows network formed by severing the cross stitching.

Fig. 5 is a view in elevation of a part of apparatus by which a continuous roll of network may be continuously made.

Fig. 6 is a plan view and section indicated by VI—VI, Fig. 5.

Fig. 7 shows a unit assembling rack or form used in making mops.

Fig. 8 is a view in elevation of exemplary severing apparatus usable with the rack-form shown in Fig. 7.

Fig. 9 is a plan view and section indicated by IX—IX, Fig. 8.

Performing the improved method, a plurality of substantially parallel, adjacent lengths of yarn 1 are laid. This may be done in various ways, some of which are hereinafter described. The parallel lengths are connected by a plurality of substantially parallel, transverse rows of cross

stitching 2. The latter should be spaced apart according to the size of the meshes desired. For instance, if the meshes are to be 1½ inches square, the rows of cross stitching then should be 1½ inches apart. A lock stitch which will not unravel should be used and it may be desirable to re-inforce the stitching with tape 3. It may also be desirable to pass the sewing thread through rubber or other insoluble cement to further prevent unraveling.

Meshes are formed by severing the stitching between alternate strands in alternate rows. There will be two sets of alternate rows of cross stitching, 4 and 5. In one set of rows the severings 6 are made opposite unsevered stitches 7 in the other set.

A continuous roll of textile network may be continuously produced with the apparatus illustrated in Figs. 5 and 6. First, each of the yarn lengths can be fed from individual spools or rolls to form the plurality of parallel rows by any of well known devices and cross stitched as above described. Then the fabric thus formed may be continuously fed, rack like, to a plurality of thin sprocket wheels 8 provided with knives 9 secured adjacently to the spaces between the sprocket teeth and arranged in the staggered relation shown. An idler roller 10 or other suitable device, may press alternately staggered stitches to the knives and cause the severances required to reticulate the fabric continuously. Guides 11, or others of like effect, should be used to align the strands feeding to the sprockets. It will be understood that the sprockets are mounted on the shaft 12, revoluble in bearings 13 and supported by the frame 14. The sprockets may be driven by any suitable mechanism or by the rack-like fabric in transit.

With intermittent feed, the fabric may be simultaneously cross-stitched and reticulated, the sewing mechanism being positioned on the strand line.

Individual units of network, such for example as those required for mop-swabs, may be made by the improved method with apparatus shown in Figs. 7, 8 and 9. Referring to Fig. 7, a continuous yarn strand 15 is helically wound on the collapsible mop form 16, ends of the yarn being held in clips 17. Then the forms supporting the yarn strands 18 are fed to sewing apparatus having gangs of needles arranged to make the required rows of cross stitchings 19. Then the severances 20, as above described, are made with apparatus shown in Figs. 8 and 9. A table 21 and frame 22 carry vertical guides 23 on which is mounted a

reciprocating carriage 24. Cross members 25 support a plurality of knives 26 set in staggered or zig-zag arrangement. The carriage and knives may be reciprocally operated by air or steam in the cylinder 27, or by a hand lever, pedal or other arrangement. The forms supporting the cross stitched yarn strands are placed on the table and positioned by the guides 29 and the strands alined to the knives by the guides 28. 10 With one stroke, this apparatus may convert the entire unit into network.

For disclosure, I have described a simple embodiment of my invention and some of the apparatus by which it may be performed, with the understanding, however, that I am not thereby 15 to be specifically limited.

I claim and desire to protect by United States Letters Patent the following combinations and their equivalents:

1. The method of forming textile network consisting of laying yarn strand in a plurality of substantially parallel stretches, sewing the same transversely with a plurality of substantially parallel rows of stitching and severing stitches between alternate strands in alternate rows, the severings in one set of rows being disposed oppositely to unsevered stitches in the other set.

2. The method of forming textile network including helically winding yarn strand to form a plurality of substantially parallel adjacent stretches, sewing the same with a plurality of substantially parallel rows of stitching and severing the stitches between said stretches, the severances being disposed zig-zag from row to row.
